ETIENNE MARÈS, OF PARIS, FRANCE.

ELECTRIC METER.

SPECIFICATION forming part of Letters Patent No. 440,431, dated November 11, 1890.

Application filed February 26, 1890. Serial No. 341,794. (No model.)

To all whom it may concern:

Be it known that I, ETIENNE MARÈS, of Paris, France, have invented a new and Improved Meter, of which the following is a full, clear, and exact description.

5 The object of the invention is to provide a new and improved meter, which is simple and durable in construction, very effective in operation, and adapted for all purposes for which meters are generally employed, especially, however, for measuring electricity and other fluids and substances.

10 The invention consists of a balanced lever on which is mounted to travel a carriage adapted to engage a registering wheel or cylinder.

15 The invention also consists of certain parts and details and combinations of the same, as will be hereinafter fully described, and then 20 pointed out in the claims.

25 Reference is to be had to the accompanying drawings, forming a part of this specification, in which similar letters of reference indicate corresponding parts in all the figures.

30 Figure 1 is a sectional side elevation of the improvement as arranged for measuring electricity, on the line $x-x$ of Fig. 2. Fig. 2 is a plan view of the same. Fig. 3 is a side elevation of the improvement. Fig. 4 is a side elevation of the same in a different position. Fig. 5 is a side elevation of the improvement in a modified form. Fig. 6 is a similar view 35 of the same in another position. Fig. 7 is an enlarged end view of the locking mechanism for the balanced lever, which latter is shown in section. Fig. 8 is a front view of the same in an unlocked position. Fig. 9 is a similar view of the same in a locked position. Fig. 10 is an enlarged transverse section of the balancing- 40 lever and the carriage. Fig. 11 represents detail side and end views of the locking-arm for the locking mechanism, and Fig. 12 is an enlarged side elevation of part of the carriage.

45 The improved meter is provided with a balancing-lever A, fulcrumed at a knife-edge B, and on which is mounted to travel a carriage C, adapted to engage and disengage a wheel D, connected with the registering apparatus E, as shown in Figs. 1 and 2. The carriage 50 C is provided with a platform C', mounted on

wheels C², traveling in a groove A', formed in the top of the balancing-lever A, (see Fig. 10,) and from the said platform extend obliquely downward, the rods C³, supporting a weight 55 C⁴, preferably a casing filled with shot.

The weight C⁴ is arranged below the knife-edge B of the lever A, so as to bring the center of gravity in a vertical line which passes through the knife-edge of the lever. When 60 the lever A is in its normal horizontal position, as shown in Fig. 3, and the carriage travels on the same, then the wheel D is turned by contact with the platform C' of the rolling carriage; but when the lever A 65 oscillates in one direction, as shown in Fig. 4, the carriage disconnects from the wheel and the latter stops turning. Thus the essential point of the invention is a carriage mounted to travel on an oscillating lever and adapted 70 to engage or disengage the controlling-wheel of a registering apparatus, which may be of any approved construction.

In Figs. 5 and 6, for instance, is illustrated a carriage C, which is provided on its platform C' with a stylus or marker F, adapted to mark on the periphery of the cylinder D', which is mounted to turn. The lines traced along the cylinder are parallel to the axis of the same, and vary in length according to the 80 length of time the stylus F is in contact with the said cylinder D', which latter in this case is substituted for the wheel D, previously mentioned. As illustrated in Figs. 1 and 2, the above-mentioned main feature of the invention is applied to an electric meter, presently to be more fully described.

The improved electric meter is mounted on a suitable base G, supporting the posts G', in which are mounted the knife-edges B of the 90 lever A. On top of the lever A travels the carriage C, in a manner previously described, and adapted to be moved with its platform C' in contact with the wheel D of the recording apparatus E. Directly below the front end 95 of the lever A is arranged a Watt meter H, comprising the coarse-wire bobbins H' and H², between which is arranged the fine-wire bobbin H³ in the usual manner, as plainly shown in Fig. 1. The fine-wire or center bobbin H³ is engaged by a wooden block I, held 100 on a wooden rod I', extending upward through

the central opening of the bobbins H^2 and H' to be hooked onto a collar I^2 , held adjustably on the front end of the balancing-lever A , and adapted to be secured in place by a set-
5 screw I^3 . On the base G are arranged the binding-screws J , J' , J^2 , and J^3 , of which the binding-screws J and J' connect the apparatus with the source of electricity, which may be a dynamo, accumulator, &c. The
10 binding-screws J^2 and J^3 connect the apparatus with the lamps or other means for using the electricity. The shunt-wire H^4 leads from the fine-wire bobbin H^2 to the binding-post J , and another wire H^5 leads from the said fine-wire bobbin H^2 to the binding-screw J' , as is plainly shown in Fig. 1.

On the base G is held in a suitable casing K a clock-work or other means for imparting a rotary motion to a crank-disk K' , connected
20 by a pitman K^2 with a lever L , fulcrumed at its lower end on a shaft L' , mounted to turn in suitable bearings erected on the base G . The upper end of the lever L is provided with a slot L^2 , engaged by a pin N' , held on the
25 outer end of a rod N , supported on grooved rollers N^2 , mounted on suitable posts erected on the base G . On the under side of the rod N is held a downwardly-extending projection N^3 , from which extends sidewise a pin N^4 , adapted to engage alternately the pins C^5 and C^6 , secured on the under side of the platform C' of the carriage C. On the shaft L' is also fulcrumed a lever O, adapted to engage with its upper end a pin P' , held on a lever P, fulcrumed on the balancing-lever A. On the lower end of the said lever P is arranged a pin P^2 , adapted to be engaged by a hook Q, held vertically adjustable on a bracket R, secured on the base G . The oscillating movement
35 of the balancing-lever A is limited by the stop-screws S and S' , arranged on the sides of the knife-edge B, as is plainly shown in Fig. 1.

The operation is as follows: The current of
45 electricity passes from its source to the binding-screw J , then to the binding-screw J^2 , passing at the same time through the coarse-wire bobbins H' and H^2 of the Watt meter H, then re-enters the apparatus by the binding-screw J^3 after having passed through the lamps or other means of using the electric current. The current then returns to the dynamo or other source of electricity by the binding-screw J' . The wires H^4 and H^5 are
50 used—one before the entrance of the current into the apparatus and the other when the current has passed through the apparatus. Now, supposing that at first no current passes through the apparatus, then the carriage C is
55 moved so that the center of gravity of the balancing-lever A is displaced and the lever is oscillated immediately upon its knife-edge B, so that the platform C' of the carriage disconnects from the wheel D, which consequently does not turn and the meter is not operated. Now, if the current passes through the apparatus the bobbin H^2 is attracted by

the bobbin H^3 and repelled by the bobbin H' . The fine-wire bobbin H^2 thus presses on the block I, thereby swinging the balancing-lever 70 A downward at its front end in the direction of the arrow a' , so that the front end of the balancing-lever rests on the set-screw S. The carriage C now travels on the balancing-lever A until it reaches such a position that its 75 weight C^4 will be sufficiently distant from the knife-edge B to balance the force applied to the end of the balancing-lever A through the bobbin H^2 . As the lever A oscillates, the pin P^2 of the lever P hooks onto the hook Q, thus 80 locking the lever A in position and preventing its rising on the return-stroke of the carriage. The pin P^2 is disconnected from the hook Q when the lever P is operated on by the lever O, which engages the pin P' and 85 swings with the lever L, imparting motion to the carriage C by means of the rod N, supporting the pin N^4 , acting alternately on the pins C^5 and C^6 on the platform C' of the carriage.

It is understood that the distance traveled by a point on the circumference of the wheel D is equal to the distance traveled by the platform of the carriage C at the moment of the balancing-lever A is upset. Thus it will 95 be seen that the wheel D is actuated at regular intervals, and the result can be read on the dial of the registering apparatus E to quickly calculate the electric power for a given time.

It is understood that the electro-dynamometer develops a force expressed by E. I. and integrated periodically at equal intervals of time. The length of the platform of the device is proportional to that force E. I., so that 105 the time during which the platform operates the counting-wheel is indicated and can be read on the dial; but this reading also gives the expression E. I. T.—that is, the electric power for a given time.

It is understood that the mechanism in the box K for imparting motion to the levers L and O and to the carriage C may be of any approved construction—an electric-clock movement, spring movement, or other device.

Having thus fully described my invention, I claim as new and desire to secure by Letters Patent—

1. In an electric meter, the combination, with the balancing-lever mounted to oscillate and an electro-magnetic device for actuating said lever, of a carriage on the lever, mechanism for reciprocating the carriage, and a registering device in the path of the carriage and separate and independent of the carriage and lever, substantially as set forth.

2. In an electric meter, the combination, with the balancing-lever mounted to oscillate and an electro-magnetic device for actuating said lever, of a carriage on the said lever, 130 clock mechanism for reciprocating the carriage, and a register separate and independent of the carriage and lever and having a wheel or cylinder the lower side of which is

in the path of the upper side of the carriage, substantially as set forth.

3. In an electric meter, the combination, with the balancing-lever mounted to oscillate, 5 the coarse-wire bobbins, intermediate-spaced fine-wire bobbin, and a connection between the front end of the lever and the fine-wire bobbin, of a carriage on the lever, a reciprocating rod mounted in bearings above the lever and connected with the carriage, and a register actuated from the carriage, substantially as set forth.

4. The combination, with the balancing-lever and an electro-magnetic device for depressing the front end of the lever, a catch for engaging the lever at the opposite side of its fulcrum, and means for releasing the catch, 15 of a carriage mounted on the lever and mechanism for reciprocating the carriage and releasing the catch, substantially as set forth.

5. The combination, with the balancing-le-

ver having an electro-magnetic device below one end for depressing it, a catch below its opposite end, and a locking-lever having a pin to engage said catch, of a carriage on the said 25 balancing-lever, a longitudinally-reciprocating rod above and connected with said carriage, a rock-shaft having a lever engaging said rod, and a lever O to engage said locking-lever, substantially as set forth.

30

6. The combination, with the balancing-lever having an electro-magnetic device for oscillating it, of a carriage having a weight adapted to register vertically with the fulcrum of said lever, mechanism for reciprocating the carriage, and a relatively-stationary register actuated by said carriage, substantially as set forth.
